UNITED STATES PATENT OFFICE.

WILLIAM G. WOOD, OF BERKELEY, CALIFORNIA, ASSIGNOR TO BERKELEY LIGHT CORPORATION, OF SAN FRANCISCO, CALIFORNIA, A CORPORATION OF NEVADA.

HEADLIGHT.

1,403,280.

Specification of Letters Patent. Patented Jan. 10, 1922.

Application filed August 5, 1918, Serial No. 248,303. Renewed September 25, 1920. Serial No. 412,832.

To all whom it may concern:

Be it known that I, WILLIAM G. WOOD, a citizen of the United States, residing at Berkeley, in the county of Alameda and State of California, have invented new and useful Improvements in Headlights, of which the following is a specification.

This invention relates to headlights and more particularly to headlights adapted for 10 automobiles and the like.

The object of the present invention is to provide means for projecting a cone-shaped beam and to provide a window or transparent opening which is circular in shape and 15 considerably reduced in area, thereby eliminating all objectionable glare or blinding effect, as the vertical height of the beam is also in this instance limited. In this lamp, viewed from points above a horizontal plane 20 of the elevation of the lamp, neither the source of light, nor the apparent source are in evidence, therefore, there can be absolutely no glare.

Another object of the invention is to provide 25 a novel form of projecting reflector and a support for the same, together with means for adjusting the vertical angular position of the headlights with relation to the forks in which they are mounted.

Another object of the invention is to provide 30 means for converging or diverging the light beam as it passes through the transparent aperture to increase or decrease the area lighted, and to produce a more uniform field of light, and also to provide means for increasing or decreasing the 35 spread of the beam vertically without affecting the spread of the beam horizontally or vice versa.

Further objects will hereinafter appear.

The invention consists of the parts and the construction and combination of parts as hereinafter more fully described and claimed, having reference to the accompanying 45 drawings in which—

Figure 1 is a central, vertical, longitudinal section through the lamp.

Fig. 2 is a diagrammatic view, showing 50 how the parabolic curvature of the projecting reflector is obtained.

Fig. 3 is a plan view of the lamp.

Fig. 4 is a front view of the same.

Fig. 5 is a diagrammatic view showing 55 how the placing of the lens may converge or diverge the beam.

Fig. 6 is a diagrammatic view showing how the spread of the light beam may be increased or decreased vertically.

Fig. 7 is a detail side elevation of the bracket support 23.

Referring to the drawings in detail, A indicates in general a lamp casing, in this instance, constructed of two sections 2 and 3, which are adapted to be secured together by means of snap hooks, generally indicated at 4. The casing is substantially egg-shaped, when viewed from a side elevation, but is comparatively long and narrow when viewed from a plan or end view, as shown in Figs. 3 and 4.

The casing is provided with a window or transparent opening 5 of exceedingly small area. This window is circular in shape and in actual practice is generally less than half an inch in diameter. The window proper is 70 secured in a mounting 6 which may form a portion of the lower casing, as here shown, and the glass may be secured in said mounting or in a screw cap 7.

Suitably secured within the lower half of 80 the casing, as by flanges 8 and rivets 9, is a reflector supporting cage 10. This cage is substantially cylindrical in shape, it being provided with an opening at each end, as at 11 and 12, for the reception of a parabolic 85 reflector 13 and a section of a parabolic reflector, such as shown at 14. The cage is also provided with a forward opening 15 through which the light rays are projected, as will hereinafter be described. Mounted 90 within the parabolic reflector is an electric bulb 16 which is preferably adjustable with relation to the axis of the reflector to prevent any portion of the filament from extending beyond the focal center, thus eliminating the projection of converging rays and simultaneously permitting the projection of substantially parallel rays against the projecting reflector 14. This reflector 14 is a section of a comparatively large parabolic 100 reflector, and, therefore, serves the function of concentrating the parallel rays received from the reflector 13; that is, all the rays projected by the reflector 14 form a cone-shaped beam and cross each other at a common focal point, which, in this instance, is located directly in the transparent aperture.

5. The rays again spread, after leaving or passing through the aperture. It can, therefore, be seen that a cone-shaped beam will be 110

projected and that the size of the aperture 5 may be exceedingly small. In theory a pin hole opening would probably be sufficient, but an opening from a quarter to a half inch 5 in diameter is preferably used as it eliminates careful adjustment of the reflectors within the casing.

The window employed in the present instance is exceedingly small when compared 10 with my copending application Serial No. 248,302, filed August 5, 1918, and with ordinary headlights employing parabolic reflectors. By this means the objectionable glaring or blinding effects generally produced by 15 ordinary headlights are entirely eliminated, because neither the source of light nor the apparent source of light is in evidence, and also because the vertical projections of the light rays are limited.

20 By referring to the diagrammatic illustration shown in Fig. 2, it will be seen that the projecting reflector 14 is nothing more nor less than a small section of a comparatively large parabolic reflector, such as 25 shown at 17, the section taken being indicated at 18. The focal point of the reflector 17 is indicated at 19 and the section 18 employed depends entirely upon the position of the parabolic reflector 13. This reflector 30 should always assume a position where its longitudinal axis will run parallel with the longitudinal axis 20 of the reflector 17. The parallel rays projected by the reflector 13 will thus strike the section shown at 18 and 35 this section will project a cone-shaped beam, the rays of which will cross each other at the focal point 19 of the reflector 17. The lower edge of the reflecting projector 18 does not extend below the horizontal line shown at 40 21—21. Thus no projected rays after leaving the aperture will pass above this horizontal line while the majority of the rays projected by the cone-shaped beam 22, after they leave the aperture 5, will strike the 45 roadway a suitable distance ahead of the car and spread laterally and give a wide field of light.

The lamp shown in the present instance is adapted to be supported by forks of the usual 50 construction by means of a pair of lugs 23 which project through the sides of the lamp casing. These lugs are provided with set-screws 24 to permit them to be rigidly secured to the forks, but it is nevertheless possible to tilt the lamp vertically, if desired, 55 as the lugs are carried by or formed integral with grooved bearing disks 25 turnably mounted in the reflector cage 10. A pair of set-screws 26, one being arranged on each 60 side of the lamp casing, pass through slotted arms 26' formed integral with the outer disks, see Fig. 7, and when tightened up, secures the lamp in any adjusted position desired. It can, therefore, be seen that although the projecting reflector 18 will not

project any light rays above the horizontal line 21—21, by tilting the lamp as a whole it is possible to raise or lower the projected beam as desired.

By referring to Figs. 1 and 5 it will be 70 seen that a plano convex lens has been placed in the transparent aperture. This lens has two functions, first, that of converging or diverging the light beam projected, and secondly, that of producing a more uniform 75 light field.

By referring to the diagrammatic view shown in Fig. 5 it will be seen that positioning of the lens behind the focal center 50 of the light beam diverges the beam as shown 80 by lines 51, while placing of the lens ahead of the focal center converges the beam as shown by the lines 52.

Practical experience has proven that these results are obtained, and also that a more 85 uniform field of light is produced, whether the lens is placed in one position or another, or at any intermediate point.

While one type of lens is here shown I wish 90 it understood that any other lens or combination of the same, that is, a compound lens or the like, may be employed.

By placing a plano convex lens of the cylinder type ahead of the focal point as shown at 53 in Fig. 6, it can readily be seen that it 95 is possible to decrease the spread of the beam horizontally or vice versa. For instance, it may be desired to limit the vertical spread of the beam to permit it to be thrown further ahead of the car, while it is simultaneously 100 desirable to maintain as wide a spread of the beam as possible to cover the entire width of the roadway. This can readily be accomplished by employing a plano convex lens of the cylinder type such as shown at 54. See 105 Fig. 6. The type of lens shown in Fig. 5 will, of course, spread or converge the entire beam, while the lens shown in Fig. 6 will spread or converge the beam in one direction only without affecting the spread in the opposite direction.

This application is a continuation in part 110 of my prior application, Ser. No. 209,834, filed Jan. 2, 1918, patented Dec. 9, 1919, No. 1,324,288.

Having thus described my invention, what I claim and desire to secure by Letters Patent is—

1. A lamp comprising a casing, having a small light emitting aperture therein, a 120 source of light in the casing, means for projecting light therefrom in the form of parallel rays, and a projecting parabolic reflector to receive the parallel rays, said projecting reflector being of a shape and character to reflect all parallel incident rays in the form of a cone shaped beam wherein all of the rays of said beam will be focused at a common point located within the light emitting aperture.

2. A lamp comprising a casing having a small light emitting aperture formed therein, a source of light in the casing, a projecting reflector within the casing in the form of a portion of a paraboloid, means for projecting a beam of substantially parallel rays from the light source to the reflector, said reflector having the focal point of its reflected rays located within said light emitting aperture.
3. A headlight comprising a casing, a projecting reflector within the casing, said projecting reflector being a section of a parabolic reflector, a small transparent aperture formed in the casing at the focal point of said projecting reflector, a source of light within the casing, and a parabolic reflector surrounding said light adapted to project a beam of substantially parallel rays against the projecting reflector, said rays being re-reflected and projected in the form of a cone-shaped beam through the transparent aperture.
4. A headlight comprising a casing, a projecting reflector mounted with said casing, said reflector being a section of a parabolic reflector, a source of light within the casing, a parabolic reflector surrounding said light and adapted to project a beam of substantially parallel rays against the projecting reflector, said last named parabolic reflector having its longitudinal axis mounted in parallelism with the longitudinal axis from which the first-named parabolic sectional reflector is taken, and a small transparent aperture formed in the casing at the focal point of said projecting reflector to permit the forward projection of a cone-shaped beam from the projecting reflector.
5. A headlight comprising a casing, a projecting reflector mounted within said casing, said reflector being a section of a parabolic reflector, a source of light within the casing, a parabolic reflector surrounding said light and adapted to project a beam of substantially parallel rays against the projecting reflector, said last named parabolic reflector having its longitudinal axis mounted in parallelism with the longitudinal axis from which the first-named parabolic sectional reflector is taken, a small transparent aperture formed in the casing at the focal point of said projecting reflector to permit the forward projection of a cone-shaped beam from the projecting reflector, the rays of said forwardly projecting beam having a focal point where they cross each other before leaving the casing and said aperture being positioned approximately at said focal point and having an area slightly larger than a cross section taken through the crossing or focal point of the rays.
6. A headlight comprising a casing, a reflector cage rigidly secured within said casing, a parabolic reflector secured in one end of said cage, a section of a parabolic re-
- flector secured in the opposite end of the cage, a transparent aperture formed in the forward end of the lamp casing, an opening formed in the forward end of the reflector supporting cage and a source of light within the first named parabolic reflector.
7. A headlight comprising a casing, a projecting reflector within the casing, said projecting reflector being a section of a parabolic reflector, a small transparent aperture formed in the casing adjacent the focal point of said projecting reflector, a source of light within the casing hidden with respect to the transparent aperture, a parabolic reflector surrounding said light adapted to project a beam of substantially parallel rays against the projecting reflector, said rays being re-reflected by the projecting reflector and projected in the form of a cone-shaped beam through the transparent aperture, and means for modifying the spread of the cone-shaped beam as it passes through the transparent aperture.
8. A headlight comprising a casing having a small light emitting aperture, a single source of light in the bottom of the casing, means cooperating with the source of light to project a beam therefrom in the form of parallel rays, means in the upper portion of the casing to receive the parallel rays and project them in the form of a cone-shaped beam, the rays of which cross within said aperture, said parts being so arranged that the axis of the cone-shaped beam, after leaving the aperture, will be directed downwardly with the uppermost divergent rays thereof on a substantially horizontal line.
9. In a lamp or projector a source of light, means cooperating therewith to project a beam of parallel rays and a reflector to receive said parallel rays and project them out in the form of a cone-shaped beam, said reflector being formed of a section of a paraboloid, having its principal axis parallel with the incident rays but located to one side of the incident beam.
10. A lamp comprising a casing having a small light emitting aperture, a single source of light located in said casing out of line with the axis of the light emitting aperture, means cooperating with the source of light to project a beam of parallel rays, and means within the casing to receive the parallel rays and project them out from the casing in the form of a cone-shaped beam with the apex of the cone lying within the light emitting aperture.
- In testimony whereof I have hereunto set my hand in the presence of two subscribing witnesses.
